UNITED STATES PATENT OFFICE

JOSEPH H. CHADBOURNE, OF DANIELSON, CONNECTICUT, ASSIGNOR TO E. H. JACOBS MFG. CO., OF DANIELSON, CONNECTICUT, A CORPORATION OF CONNECTICUT

LUG STRAP

Application filed June 27, 1929. Serial No. 374,116.

My present invention relates to lug straps for looms and more particularly to an improved lug strap and method of making the same.

5 Lug straps as made at the present day are invariably made of one or more pieces of ticking or duck cemented and rolled flat and pressed flat together and later bent into a U shape so as to better receive the picker stick 10 and to withstand the pounding that so soon destroys the usefulness of the strap. In making the prior types of lug straps it has been usual to take a plurality of superimposed pieces of ticking or duck and roll the same 15 up into an elongated roll which is pressed flat and allowed to set and is afterwards bent into a bow or U shape. This step in the method of manufacture, namely, of bending the lug after the fabric has been glued and pressed, 20 places an undue strain on the outermost layers of the duck or ticking and it has been found that the greatest percentage of failures occur at the outside of the bend of the strap. This is necessarily so as the entire strain to 25 which the strap is subjected is placed on a relatively few of the outer layers of ticking or duck. The inner layers are wrinkled, slack and ruptured.

Such older forms of lug strap have a plug 30 fitted in at the heel and held in position by a rivet passing therethrough and through the sides of the strap. It is impossible to force the plug into close contact with the heel and the entire strain of working comes on the 35 rivet, with the result that a great deal of the breakage occurs at the point where the rivet passes through the sides. This strain on the portion where the rivet passes through is intensified when it is considered that the lugs 40 will creep, that is, one side will become longer than the other when in use, and if the lug strap then has its position in the loom changed, the entire strain comes on one of the side pieces only. As the older form of lug 45 strap was bent into shape after the glue, or other adhesive used, had set, the relation of the various layers with respect to each other was disturbed.

In my present invention I have devised an 50 improved method of manufacture by which

is produced a lug strap of superior quality and in practicing my improved method I form the lug strap of a plurality of layers, each successive layer being built into practically the form in which the lug strap is to 55 ultimately take, and during the building up operation incorporate therein various short strips of reinforcing material and also strips of material that form the rounded inner face of the lug strap. The resultant lug strap is 60 a structure in which each layer performs its share of the work and the pressure and tensions being evenly distributed, I have been able to eliminate the greater percentage of breakage, such as occurred at the bend in 65 former types of lug straps.

Reinforcing devices, such as projections, indentations, or cords or wires act not only as a reinforcement but also serve to bind the layers together in such a manner as to firmly 70 prevent slippage of the layers with respect to each other. Also, by building the plug in the heel I am able to dispense entirely with the use of rivets and the entire lug strap assembly comprising the sides, heel, plug and 75 reinforcements, becomes a single homogeneous mass. By building the lug strap of a plurality of layers placed on each other in the position they will occupy in service, there is no disturbance between the various layers and 80 also the more tension placed on the lug strap in service, the closer the various elements are brought together at the heel.

An object of my invention, therefore, is 85 an improved method of manufacturing lug straps for looms and the like.

Another object of my invention is an improved lug strap.

Referring to the drawings illustrating a 90 preferred embodiment of my invention and mechanism by which my improved method may be economically practiced;

Fig. 1 is a side elevation of a lug strap;

Fig. 2 is a plan view of Fig. 1;

Fig. 3 is a section on the line 3—3 of Fig. 1 but showing a groove substituted for a rib;

Fig. 4 is a section on the line 4—4 of Fig. 2;

Fig. 5 is a section on the line 5—5 of Fig. 2;

Fig. 6 is a perspective view of the mandril employed in practicing my invention;

5 Fig. 7 is a perspective view of a mould utilized in connection with Fig. 6;

Fig. 8 is a side elevation of a lug strap in position on a mould block similar to Fig. 6, and surrounded by a mould such as is illustrated in Fig. 7, and

10 Fig. 9 is a side elevation of Fig. 8.

Referring to the drawings, 10 designates a complete lug strap formed of a plurality of layers of fabric or other suitable material 11, such fabric being formed to build up a U-shaped structure. Referring to Fig. 2 it will be noted that the legs of the U-shaped structure constituting the lug strap 10 are tapered, being gradually larger, moving from right to left in such figure, and this enlargement is made possible by the insertion at various points of pieces of fabric 12 of less length than the layers of fabric 11. Also the connecting portion of the legs of the lug strap 10 has incorporated therein additional pieces 13 of fabric and also there is formed of the layers 11, fabric pieces 12, and reinforcing pieces 13, an inner ball member 14. The inner and outer faces of the legs of the lug strap 10 have formed therein out of the fabric longitudinally arranged ribs 15, such ribs on the inner end extending as far only as the ball member 14. I may, if it is deemed advisable, omit either the 20 inner or the outer, or both, of the ribs 15 and may insert in addition thereto, or in place thereof, or omit entirely, parallelly arranged reinforcing members 16 which may be of cord, yarn, rawhide or metal of any 30 suitable character. The various layers of fabric 11, 12, and reinforcing pieces 13 are held together by any suitable adhesive and I am not to be limited in this regard to any particular type of adhesive. The lug strap 10 is preferably subjected during the manufacturing operation to pressure and after completion there is formed, adjacent the ends of the legs thereof, elongated slots 17, through which may pass the usual holding 40 bolts. In place of the reinforcing ribs 15 I may substitute depressed grooves 18 either on the inner or outer faces or on both the inner and outer faces.

While the improved lug strap above described may be built by hand, I prefer from a manufacturing standpoint to build the same with the addition of moulding apparatus such as is shown in Figs. 7, 8 and 9, and referring to such figures, 20 designates a mould 50 block which may be provided on opposite faces with longitudinally extending ribs 21, or such ribs may have substituted therefor longitudinally extending grooves 22. Preferably the mould block 20 is of sufficient 60 length to enable two lug straps 10 to be manu-

factured thereon and for this purpose I have mounted such mould block 20 on a suitable shaft 23 and mount such shaft so as to have the same rotatable in suitable bearings (not shown). On the ends of the mould block 20 70 I form depressions 24 in which the ball member 14 of the lug strap 10 may be formed. With such a mould block I preferably take a strip of fabric or other suitable material 11, wind a layer completely around the block 20, 75 apply adhesive to the outer face of such layer, wind a succeeding layer, and apply adhesive after each layer is placed in position. At the proper times I add to the structure being built up on the block 20, the reinforcing layers 12, passing the same over the ends of the block 20 and at the proper time add to the top of each block the reinforcing members or layers 13. After a sufficient number of layers of fabric 11, 12, and 13 have been placed on the block 20, I slide over such completed member the outer mould casings 25, such outer mould casings being provided on the inner faces thereof with parallelly arranged grooves 26, or with parallelly arranged ribs 27, or I may omit the same if desired. Also, 80 it should be understood that at the proper time I place on the being-built-up structure the parallelly arranged reinforcing members 16. After the structure is built and the outer mould casings placed thereon, the entire mould is placed in a compressing apparatus, where the being-built-up structure is allowed to set, after which the built-up structure is cut 85 apart to form a pair of lug straps, such as is 90 shown in Figs. 1 and 2, it being understood that after this cutting operation is performed the elongated slots 17 are cut in the side walls of the lug strap.

It will be apparent that this method of 105 building a lug strap insures that the layers of fabric 11, 12 and 13 conform to the final shape of the finished product and, therefore, that each layer when a lug strap is in operation is subjected to the same stress or strain. 110 Also in this form of lug strap all rivets are omitted, being unnecessary, and therefore there is no danger of breakage due to perforating the material unnecessarily. Being subjected to equal stresses and strains there is 115 no tendency for the outer layers 11 and 12 to break in use as is the case in former types of lug straps where a final shape is only given to the lug strap after the various layers are incorporated into a unitary structure. It 120 should be understood that in former types the inner layers are subject to compression during the manufacturing operation, while the outer layers are subject to tension and in 125 use the breakage in ninety percent or more cases occurs at the outer end face or at the left hand end of the structure shown in Fig. 5.

By building the legs of the U-shaped structure tapered, it is possible to use existing hold- 130

ers and insert material into the structure at the place where the strain is greatest.

I may, if it is desired, make a mould consisting of practically a plurality of elements such as shown in Figs. 6, 7, 8 and 9, arranged side by side and form a plurality of lug straps 10 at a single operation and after the building and compressing operations are performed saw the combined unit into separate elements, 10 such as shown in Figs. 1 and 2.

Having thus described my invention what I claim as new is:

1. That improved method of manufacturing lug straps which consists in forming a strip of fabric into a U-shaped form, adding successive layers of material thereto, applying reinforcing material thereto as the successive layers are added, incorporating the successive layers and reinforcing material into a unitary structure by the use of adhesive.

2. That improved method of manufacturing lug straps which consists in forming a strip of material into substantially U-shaped form, adding successive layers thereto by the use of adhesive, applying reinforcing material as the structure is built up, forming ribs on the legs of the U-shaped fabric forms, and subjecting the built-up structure to pressure.

3. That improved method of manufacturing lug straps which consists in forming a layer of fabric about a rectangular mandril so as to cause the fabric to form a substantially U-shape, adding successive layers thereto by the use of adhesive, applying reinforcing layers of material at the proper places and times, adding reinforcing rods thereto and extending parallel to the length of the legs of the U-shaped forms, and forming reinforcing ribs on the inner and outer faces of the legs by means of pressure.

4. That improved method of manufacturing lug straps which consists in forming a strip of material in substantially U-shaped form and predetermined length, adding successive layers of substantially the same length as the first layer and attaching the same to preceding layers by the use of adhesive, applying reinforcing material to the layers as the structure is built up, said reinforcing material being of less length than the first said strip, forming ribs on the legs of the U-shaped forms out of the material of which the legs are composed and subjecting the built up structure to pressure.

5. In testimony whereof, I have signed my name to this specification.

JOSEPH H. CHADBOURNE.
